BRASSIÈRE

Anne Walters, New York, N. Y.

Application March 9, 1938, Serial No. 194,771

3 Claims. (Cl. 2—42)

This invention relates to new and useful improvements in a brassière.

The invention has for an object to construct a brassière characterized by a peculiar bust construction which is adapted to effectively support the busts.

More specifically, the invention proposes the provision of bust support bands located within each of the bust cups of a brassière body band and resiliently connected with the bust cups at certain points and fixedly connected with straps at other points, these latter straps being connected with one of the ends of the shoulder straps of the body band. With this arrangement all carrying loads upon the bust cups are transmitted directly to the shoulder straps. It is thus possible to better support the busts.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of a brassière constructed according to this invention.

Fig. 2 is a rear view of Fig. 1.

Fig. 3 is a fragmentary enlarged sectional view taken on the line 3—3 of Fig. 2.

Fig. 4 is a fragmentary horizontal sectional view taken on the line 4—4 of Fig. 1.

In the form of the invention illustrated the brassière comprises a body band 10' formed with openings 11' for the busts to extend in, and shoulder straps 12 attached at one of their ends to the body band at the top edges of the bust openings 11' and at their other ends attached to portions of the body band which are at the back when the brassière is being worn. These shoulder straps 12 are adapted to extend over the shoulders and assist in holding the brassière in position. Bust cups 13' are mounted on the body band 10' over the openings 11' and have their outer edges 13' set outwards from the edges of the openings 11' and attached to the material of the body band 10' by stitches 14.

Each of the bust cups 13' is formed with several darts 15' to give the bust cup its hollow shape. The body band 10' is formed with finished edge portions 10a, and with an end elastic section 10b. Fastening elements 16 are mounted upon ends of the body band for engagement with each other to releasably secure the ends of the body band together when the brassière is applied to the

body. Each of the shoulder straps 12 is formed adjustable and controlled with a conventional buckle 18.

Moon-shaped bust support bands 19' are arranged to the rear of the brassière and located within the arcuate pocket formed by the edge portions of the openings 11' and the material of the bust cups 13''. Each of the moon-shaped bust support bands 19' is resiliently held at its outer ends by elastic straps 20' which are connected to its edges and to the material of the body band 10'.

Adjustable straps 21' are connected with the ends of the moon-shaped bust support bands 19' and extend through slots 35 to the outer face of 15 the bust cups. The upper ends of the adjustable straps 21' are attached by stitches 24' to the lower ends of the shoulder straps 12. Each of the adjustable straps 21' have buckles 18' intermediate of their ends upon the outer face of the brassière 20 by which they may be adjusted. It is thus possible to pull up or lift the moon-shaped bands and so change the supporting characteristics of the brassière.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A bust cup area for a brassière, comprising a portion of a body band having an opening for a bust, a bust cup mounted on said band and over said opening and having its edges attached to the edge of said band around said opening, a shoulder strap, a crescent-shaped bust support band disposed within said cup with its points directed upwards, means for resiliently attaching the bottom edge of said bust support band to the bottom edge of said bust cup, and a pair of adjustable straps each having one of their ends attached to one of the corners of said bust support band, their intermediate portions extended to the exterior of said bust cup through openings formed therein, and their other ends attached to the front end of said shoulder strap.

2. A bust cup area for a brassière, comprising a portion of a body band having an opening for a bust, a bust cup mounted on said band and over said opening and having its edges attached to the edge of said band around said opening, a shoulder strap, a crescent-shaped bust supported band dis-

- posed within said cup with its points directed upwards, means for resiliently attaching the bottom edge of said bust support band to the bottom edge of said bust cup, and a pair of adjustable straps each having one of their ends attached to one of the corners of said bust support band, their intermediate portions extended to the exterior of said bust cup through openings formed therein, and their other ends attached to the front end of said shoulder strap, said means comprising elastic straps having one of their ends attached to the bottom edge of said bust support band and the other of their ends attached to the bottom edge of said bust cup.
3. A bust cup area for a brassière, comprising a portion of a body band having an opening for a bust, a bust cup mounted on said band and over

said opening and having its edges attached to the edge of said band around said opening, a shoulder strap, a crescent-shaped bust support band disposed within said cup with its points directed upwards, means for resiliently attaching the bottom edge of said bust support band to the bottom edge of said bust cup, and a pair of adjustable straps each having one of their ends attached to one of the corners of said bust support band, their intermediate portions extended to the exterior of said bust cup through openings formed therein, and their other ends attached to the front end of said shoulder strap, said openings in said bust cup being formed midway between the corners of said bust support band and the front end of said shoulder strap.

ANNE WALTERS.
